UNITED STATES PATENT OFFICE.

WILLIAM BUNTING, JR., OF BOSTON, MASSACHUSETTS, ASSIGNOR TO THE MEYER-SNIFFEN COMPANY, (LIMITED,) OF NEW YORK, N. Y.

DESIGN FOR A WASH-BASIN SLAB.

SPECIFICATION forming part of Design No. 16,949, dated October 26, 1886.

Application filed Aug 25, 1886. Serial No. 211,867. Term of patent 14 years.

To all whom it may concern:

Be it known that I, WILLIAM BUNTING, Jr., a citizen of the United States, residing at Boston, in the county of Suffolk and State of Massachusetts, have invented and produced a new and original Design for the Slabs or Tops of Wash-Basins, of which the following is a specification, reference being had to the accompanying drawings, forming a part thereof.

10 Figure 1 is a top or plan view of a basin slab or top embodying my design. Fig. 2 is a vertical section taken at the line $x-x$, Fig. 1; and Fig. 3 is a similar section taken at the line $y-y$ of Fig. 1.

15 My design consists in a slab or top having an opening which extends rearwardly and forms a cove-like portion.

The main feature of my design rests in the presence of the cove-like portion A. The

major part B of the opening is substantially 20 ring-like in contour, and finishes off at the rear into the cove-like portion A.

Although I have shown the general outline of the slab as rectangular, I do not wish to be confined thereto, as other shapes may be 25 sorted to, my design relating particularly to the configuration of the opening in the slab.

What I claim is—

The design for a wash-basin slab herein described and shown, consisting of the opening 30 B, extending rearwardly and forming the cove-like portion A.

In witness whereof I have hereunto set my hand this 20th day of August, 1886.

WILLIAM BUNTING, JR.

In presence of—

C. H. EGLEE,
GEORGE Z. HAMOLEN.
